CLAIM

The ornamental design for a cow stuffed animal as shown and described.

DESCRIPTION

FIG. 1 is a perspective view of a cow stuffed animal showing my new design;
 FIG. 2 is another perspective view thereof;
 FIG. 3 is a front view thereof;
 FIG. 4 is a back view thereof;
 FIG. 5 is a left view thereof;
 FIG. 6 is a right view thereof;
 FIG. 7 is a top plan view thereof; and,
 FIG. 8 is a bottom plan view thereof.
